DESIGN FOR A WHEEL

J Harold Hunt and Harry J. Horn, Lansing,
Mich., assignors to Motor Wheel Corporation,
Lansing, Mich., a corporation of Michigan

Application February 27, 1935, Serial No. 55,648

Term of patent 7 years

To all whom it may concern:

Be it known that we, J Harold Hunt and Harry J. Horn, citizens of the United States, residing in Lansing, in the county of Ingham and State of Michigan, have invented a new, original, and ornamental Design for a Wheel, of which the following is a specification, reference being had to the accompanying drawing, forming part thereof.

In the drawing:

Figure I is a side view in elevation of a wheel showing our new design.

Figure II is a perspective view of the wheel body shown in Figure I, and

Figure III is a sectional view taken on line III—III of Figure I.

The present design is essentially a disc-like configuration with four equally spaced radial projections at its periphery. A plurality of closely spaced radial spoke formations are provided in the disc extending inwardly from its periphery. Openings are provided in the disc between the spoke formations. A thin peripheral band located radially outwardly of these openings connects the outer extremities of the spoke portions.

We claim:

The ornamental design for a wheel as shown and described.

J HAROLD HUNT.
HARRY J. HORN.
